CLAIM

The ornamental design for a mixing bowl, as shown and
described.

DESCRIPTION

FIG. 1 is a perspective view of a mixing bowl according to
the design;

FIG. 2 is a front elevation view thereof;

FIG. 3 is a back elevation view thereof;

FIG. 4 is a left side elevation view thereof, a right side
elevation view being a mirror image of the view shown in
FIG. 4;

FIG. 5 is a top plan view thereof; and,

FIG. 6 is a bottom plan view thereof.

The portions of the article shown in even broken lines form
no part of the claimed design.

Dash-dot-dash broken lines indicate bounds of the claimed
design and form no part thereof.

1 Claim, 6 Drawing Sheets

Related U.S. Application Data

a continuation of application No. 29/739,174, filed on Jun. 23, 2020, now Pat. No. Des. 964,803.
